EYE SET

Filed Feb. 14, 1929

UNITED STATES PATENT OFFICE

SAMUEL MARCUS, OF RIVERDALE, AND ANDREW FUERTINGER, OF NEW YORK, N. Y.,
ASSIGNORS TO MARKON MANUFACTURING CO., INC., OF NEW YORK, N. Y., A COR-
PORATION OF NEW YORK

EYE SET

Application filed February 14, 1929. Serial No. 339,797.

This invention relates to an eye set, and particularly to means embodied therein by which to attach the eye set within a doll head, the invention being in the nature of an improvement over what is shown and described in the pending application of Alexander Konoff, Serial No. 141,943, filed October 16th, 1926.

An object of the present improvement is to simplify and render more efficient and more practical for quantity manufacture the supporting carrier portion of the eye set by means of which the remainder of the eye set is attached in position within the doll head.

15 A further object is to provide an improved supporting carrier formed entirely from a single piece of sheet metal including relatively movable parts by which to fix the eye set in the doll head.

20 A more detailed object is to provide a single piece supporting carrier comprising a central portion for attachment to the eyes and opposite end portions movable relative to the central portion to effect attachment of the eye set in the head.

25 A further object is to provide an improved carrier operable automatically to adjust the eyes of the set with respect to the sockets of the head in response to changes in size of the parts concerned due to shrinkage or expansion.

30 Other objects and aims of the invention, more or less specific than those referred to above, will be in part obvious and in part 35 pointed out in the course of the following description of the elements, combinations, arrangements of parts and applications of principles constituting the invention; and the scope of protection contemplated will be indicated in the appended claims.

40 In the accompanying drawings which are to be taken as a part of this specification, and in which we have shown merely a preferred form of embodiment of the invention:—

45 Fig. 1 is a rear elevational view of an eye set constructed in accordance with this invention, the set being shown as it appears when in position within a doll head, the head being illustrated in vertical section.

50 Fig. 2 is a horizontal sectional view taken

substantially upon the plane of line II—II of Fig. 1.

Figs. 3, 4 and 5 are plan views of the supporting carrier above, the different views showing different positions of the relatively movable parts of said carrier, Fig. 3 showing the parts of the carrier fully distended, Fig. 4 showing the parts as they appear when fully collapsed preparatory to insertion of an eye set into a doll head, and Fig. 5 showing the parts as they appear in normal position when attached.

55 Fig. 6 is a view similar to the right hand portion of Fig. 2 but illustrating a slight modification of the supporting carrier.

60 Referring to the drawings for describing in detail the structure illustrated therein, the reference character L indicates a doll head or the like having the usual spaced eye sockets as 1 and 2 therein. Beyond these sockets the cheek portions as 3 and 4 are preferably thickened and shaped to provide opposite interior wall surfaces as 5 and 6 which are substantially parallel to each other to thus adapt them for proper and substantial supports 70 for the eye set.

65 The eye set comprises two main elements, namely a supporting carrier G and an eye member H.

70 The supporting carrier G consists of a body portion 7 which is adapted to extend horizontally across the interior of the doll head from cheek portion to cheek portion, and a pair of arms as 8—8 intermediate its length 75 extending forwardly adapted to constitute an eye carrying portion for supporting the eye member H.

75 The eye member H consists of a cross rod 9 at opposite ends of which are mounted two eyes as 10 and 11, said eyes being connected with the cross rod in any desired manner well known in this art.

80 The supporting carrier G is made entirely from a single elongated piece of sheet metal bent into channel shape, providing a flat plate portion 12 and opposite parallel flanges as 13—13. At opposite ends of the central portion as 14 of the plate 12 said plate is cut away to provide openings as 15—15, the flanges 13—13 however continuing uninter- 85

ruptedly across said openings and constituting the sole connection between the central portion 14 and the opposite end portion 16-16 of said plate.

The forwardly extending arms 8 above mentioned are conveniently formed as bent-up portions of the sheet metal removed in the formation of the openings 15-15.

The outer ends of the portions 16-16 are shaped to provide a plurality of prongs, as 17-17, and a bent over portion constituting a stop wall as 18 facing outwardly. In use the prongs 17 are adapted to be impaled into the material of the cheek portions 3 and 4 of the doll head, and the stop walls 18 are adapted to engage directly against the wall surfaces 5 and 6 for limiting the distance to which the prongs may be thrust into said cheek portions.

Prior to inserting an eye set into a doll head it is necessary that the carrier shall be of a relatively reduced length in order that the prongs at its ends may be readily introduced to proper relative positions with respect to the wall surfaces 5 and 6 of the head. The present invention therefore contemplates that the material comprising the flanges 13-13 of the carrier shall be readily bendable in those sections as 19-19 bridging the openings 15-15. The illustration Fig. 4 suggests a form of bend which may be employed. By bowing out the sections 19 as illustrated in this figure the end portions of the carrier may be brought nearer together, while by straightening out the sections to a greater or less degree as indicated in Fig. 5 the end portions of the carrier may be moved away from each other. Also, as is apparent from these figures, any desired movement of the end portions of the carrier with respect to each other will be readily accommodated by the sections 19, said sections merely bending more or less in response to the amount of movement given to the end portions of the carrier, and serving thereafter to hold said end portions, with a desired amount of accuracy, in any position to which they are moved.

Assuming the carrier to be in the condition as illustrated in Fig. 4 and having been placed within a doll head, with an eye member H in position, but the prongs 17 having not yet been impaled within the cheeks of the head, it is simply necessary to apply force, as for instance by a suitable tool such as is shown and described in the pending application of Alexander Konoff, Serial No. 144,068, filed October 25th, 1926, to move the end portions of the carrier away from each other thus straightening out to a required extent the sections 19, as in Fig. 5, and driving the prongs into the material of the cheeks of the head. The sections 19 will hold the position into which they have thus been moved by separation of the ends of the carrier to a sufficient

degree for maintaining the prongs with a desired degree of tightness in their impaled positions. The sections 19-19 are inherently resilient and there will thus occur a slight return movement of the ends of the carrier toward each other, occasioned by the spring tendency of the sections 19 to return to their original condition. This is beneficial as a means of insuring that pressure of the opposite ends of the carrier against the opposite cheek portions of the head in the finished doll shall necessarily be something less than the maximum pressure imposed by the attaching tool.

The sections 19-19 being flexible enable forced movement of the central portion 14 in all directions with respect to the end portions to facilitate adjustment of the eyes into the sockets of the head.

As a convenient means by which to move the opposite end portions of the carrier with respect to each other and with respect to the central portion each of these portions is provided with a socket as 20 adapted to be engaged by appropriate portions of the operating tool employed as above mentioned.

It will now be noted that the plate portions 16 and their prongs 17 are wholly at one side of the vertical plane of the two flanges 13, and that said flanges, particularly the sections 19 thereof, possess a certain amount of resiliency. Because of this arrangement any pressure which may be exerted against the prongs tending to move them toward the central portion of the carrier will impose a relatively stronger bending strain against the forward marginal portions of the sections 19 of the flanges than against the relatively rearward marginal portions of said sections. Pressure endwise against the prongs, as for instance a pressure due to excessive shrinkage of the doll head, will thus produce a definite tendency to flex the sections 19 in a manner causing the central portion of the carrier to be bowed rearwardly an amount proportionate to the amount of shrinkage of the head.

The sections 19-19, being of sheet metal and being always bowed outwardly approximately as in Fig. 5 when in use, are readily bendable by force applied to the end sections. They stand substantially flatwise with respect to the line of pressure. When bent they simply take a new set, and yet are inherently capable of a certain desirable resiliency with respect to the new set position, such that they might appropriately be termed flexible leaf springs.

As illustrated in the modification Fig. 6 the stop walls 18 may be arranged to project forwardly of the plate 12 if desired as a means to increase the amount to which the central portion of the carrier may be bowed rearwardly proportionate to a given amount of shrinkage of the head.

The rearward bowing of the central portion of the carrier will of course carry with it the arms 8-8 and thus ease back the eyes 10 and 11 from their sockets, which is a desired movement in the presence of shrinkage of the head, and the amount to which the eyes are thus eased back is automatically determined by the amount of shrinkage of the head.

Whenever a supporting carrier stands bowed rearwardly as described, such bowing is of course so slight that there is ample spring tendency in the sections 19 to return them to a straight line relationship when the bowing pressure is removed. Hence, whenever under these circumstances the head again expands the carrier will follow and return the eyes forwardly.

On a warm summer day a doll head fitted with an eye set as described would dry and shrink while the metallic carrying member would expand. These opposite forces may produce pressure endwise against the carrier and bow the carrier backwardly to ease the eyes from the sockets.

The present invention thus comprises efficient means for automatically moving the eyes with respect to their sockets in response to, and in proportion to, change of size of the parts concerned, thus automatically insuring a proper fit of the eyes within their sockets under all practical conditions. It provides a simple, practical and inexpensive supporting carrier for the eyes, and it always insures a degree of loose motion between the carrier and the doll head sufficient to prevent injury to the head in use.

Mention may be here made of the fact that when an eye set is originally attached the doll head is relatively "green" and pliable so that pressure from the attaching tool is not likely to cause injury, while later, when the head is fully "cured", then care must be exercised to prevent the imposition of excessive pressure.

It will be understood of course that this automatic control of the relationship between the eyes and their sockets is of particular importance where the eyes are intended to move by gravity between open and closed positions as in the so-called sleeping dolls. A counter-weight as 21 is shown in the accompanying drawings attached to the cross rod 9 for gravity control of the eyes in the usual manner.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described our invention, what

we claim as new and desire to secure by Letters Patent is:—

1. An eye set comprising a pair of eyes and a supporting carrier therefor, a cross rod to opposite end portions of which the eyes are connected, the supporting carrier comprising an elongated member extending parallel with the cross rod with its opposite ends adjacent the eyes respectively, said carrier having a central portion and a part extending forwardly therefrom into supporting engagement with the cross rod, said carrier being a single piece of sheet metal having integral prongs at its opposite ends for being embedded within the opposite cheek portions of a doll head adjacent the eyes respectively said single piece of sheet metal having sections of itself between said central portion and said ends independently bendable to thereby render said ends movable to drive the prongs away from said central portion into embedded relation in the doll head, and said bendable sections being of a character also to hold the prongs in said embedded relation.

2. An eye set comprising a pair of eyes and a supporting carrier therefor, a cross rod to opposite end portions of which the eyes are connected, the supporting carrier comprising an elongated member extending parallel with the cross rod with its opposite ends adjacent the eyes respectively, said carrier having a portion extending forwardly therefrom into supporting engagement with the cross rod, said carrier being a single piece of sheet metal having integral prongs at its opposite ends for being embedded within the opposite cheek portions of a doll head adjacent the eyes respectively, said single piece of sheet metal having a section of itself intermediate its ends bendable to thereby render the ends movable to drive the prongs away from each other into embedded relation in the doll head, and said bendable section being resilient to thereby insure a slight return movement of the prongs after the pressure is relieved.

3. An eye set comprising a pair of eyes, attaching means therefor to be forced into impaled relation in the wall of a doll head, and means tending to reduce the degree of impalement upon relief of the impaling force.

4. An eye set comprising a pair of eyes, attaching means therefor to be forced into impaled relation in the wall of a doll head, and connecting means between the eyes and the attaching means of a character tending to reduce the degree of impalement upon relief of the impaling force.

5. A single piece supporting carrier for eye sets, said carrier consisting of an elongated piece of sheet metal, a part of said sheet metal being struck up for connection with the eyes, said piece of sheet metal having a central portion carrying said struck up part and opposite end portions for engaging opposite

wall surfaces of a doll head, said piece of sheet metal having openings formed therethrough intermediate the central portion and said end portions, and said piece of sheet metal having longitudinal marginal flanges bridging said openings bendable in the regions of said openings to permit relative movement between the central and end portions.

10 6. A single piece supporting carrier for eye sets, said carrier consisting of an elongated piece of sheet metal having a central portion for connection with the eyes and having end portions spaced from the central portion for engaging opposite wall surfaces of a doll head, and said piece of sheet metal having opposite longitudinal marginal flanges thereon constituting the sole connection between said central portion and said end portions, 15 said flanges being bendable in the regions between the central and end portions.

7. A single piece supporting carrier for eye sets, said carrier consisting of an elongated piece of sheet metal having a central portion for connection with the eyes and having end portions spaced from the central portion for engaging opposite wall surfaces of a doll head, and said piece of sheet metal having opposite longitudinal marginal flanges thereon constituting the sole connection between said central portion and said end portions, 20 said flanges being bowed outwardly from each other in the regions between said central and end portions, and being bendable to thereby facilitate relative movement between said central and end portions.

8. An eye set comprising a cross rod, a pair of eyes mounted upon the ends of said cross rod, an elongated carrier member extending parallel with the cross rod, the ends of the carrier having parts serving as anchors located adjacent the respective eyes, said carrier being a single piece of sheet metal and extensible in the direction of its length for the purpose of forcing said anchoring parts into the substance of a doll head, and for maintaining them anchored therein, and said carrier having a portion extending from it laterally and carrying said cross rod in order to support said eyes.

9. An eye set comprising a pair of eyes and a supporting carrier therefor, a cross rod to opposite end portions of which the eyes are connected, the supporting carrier comprising an elongated member extending parallel with the cross rod with its opposite ends adjacent the eyes respectively, said carrier having a portion extending forwardly therefrom into supporting engagement with the cross rod, 45 said carrier being a single piece of sheet metal having opposite end portions and an intermediate portion which serves as a connecting link between the end portions, said intermediate portion being bendable to enable movement of the end portions with respect

to each other in the direction of length of the carrier and being of a character to take a new "set" in its bent position for thereby holding the end portions in their moved positions, and said end portions having prongs integral therewith for engaging the doll head to hold the carrier connected with the doll head.

10. An eye set comprising a pair of eyes and a supporting carrier therefor, said supporting carrier comprising a single piece of sheet metal having integral prongs at its opposite ends for being embedded within the opposite wall portions of a doll head, said single piece of sheet metal having a portion of itself intermediate its ends readily bendable to render the ends movable to drive the prongs away from each other into embedded relation in the material of the doll head, said single piece of sheet metal having another portion of itself intermediate its ends connected with the eyes to support the eyes upon the carrier, and said eye supporting portion being connected with said bendable portion to be adjustable with respect to the end portions by bending of the bendable portion.

11. An eye set comprising a pair of eyes and a supporting carrier therefor, the supporting carrier comprising an elongated member having a central portion to which the eyes are connected, opposite end portions for attachment to opposite wall parts of a doll head, and connecting means between the central portion and said opposite end portions consisting solely of parts bendable to adjustably move the opposite end portions toward and away from the central portion.

12. A supporting carrier for eye sets, said carrier having a central portion for connection with the eyes, a pair of attaching portions for engaging opposite wall surfaces respectively of a doll head to hold the carrier connected with the head, and a pair of connecting portions disposed one at each side of the central portion intermediate said central portion and said attaching portions in a plane at one side of the vertical plane of a straight line between the attaching portions said connecting portions serving to connect said central portion with said attaching portions respectively and being flexible in a direction transversely of the carrier and being flexible also in the direction of length of the carrier.

13. A supporting carrier for eye sets, said carrier having a central portion for connection with the eyes, a pair of attaching portions for engaging opposite wall surfaces respectively of a doll head to hold the carrier connected with the head, and a pair of connecting portions disposed one at each side of the central portion intermediate said central portion and said attaching portions in a plane rearwardly of the vertical plane of a straight line between the attaching portions said connecting portions constituting the sole means to connect said central portion with said at-

taching portions respectively and being flexible in a direction transversely of the carrier and being flexible also in the direction of length of the carrier.

In testimony whereof we affix our signatures.

SAMUEL MARCUS.
ANDREW FUERTINGER.
